(57) **CLAIM**

The ornamental design for an enclosure for hydrogen generation system, as shown and described.

DESCRIPTION

FIG. 1 is a front, right side, and top perspective view of an enclosure for a hydrogen generation system showing the new design;

FIG. 2 is a front elevational view thereof;

FIG. 3 is a left side elevational view thereof; and,

FIG. 4 is a rear elevational view thereof.

The broken line(s), which define the bounds of the claimed design form no part of the claimed design.
